TAPE DISPENSER

Francois Le Merle, 136 Blvd. Serurier,
Paris 19, France

Filed Nov. 21, 1966, Ser. No. 4,763

Claims priority, application Germany May 24, 1966

Term of patent 14 years

(Cl. D74—1)

FIG. 1

FIG. 3

FIG. 2

FIG. 4

I claim:

The ornamental design for a tape dispenser, substantially as shown and described.
